US0D1026227S

(12) **United States Design Patent** (10) **Patent No.:** **US D1,026,227 S**
(45) **Date of Patent:** **** May 7, 2024**

(54) **INTRAORAL SCANNING SYSTEM CART**

(71) Applicant: **Align Technology, Inc.**, San Jose, CA (US)

(72) Inventors: **Zakhar Ginzburg**, Netanya (IL); **Roe Gorfinkel**, Yavne (IL); **Tom Scatter**, Tel Aviv (IL)

(73) Assignee: **Align Technology, Inc.**, San Jose, CA (US)

(**) Term: **15 Years**

(21) Appl. No.: **29/768,525**

(22) Filed: **Jan. 29, 2021**

(51) LOC (14) Cl. **24-02**

(52) U.S. Cl.

USPC **D24/185**

(58) **Field of Classification Search**

(57) **CLAIM**

The ornamental design for an intraoral scanning system cart, as shown and described.

DESCRIPTION

FIG. 1 is a front left perspective view of an intraoral scanning system cart in accordance with the claimed design. FIG. 2 is a front left perspective view thereof, showing a detached monitor.

FIG. 3 is a front view thereof, showing the detached monitor.

FIG. 4 is a rear view thereof, showing the detached monitor.

FIG. 5 is a right side view thereof, showing the detached monitor.

FIG. 6 is a left side view thereof, showing the detached monitor.

FIG. 7 is a top view thereof; and,

FIG. 8 is a bottom view thereof.

The broken lines in the figures show portions of the intraoral scanning system cart that form no part of the claimed design.

1 Claim, 7 Drawing Sheets
